DESIGN.

J. G. CHAPMAN.

EDGING.

APPLICATION FILED AUG. 2, 1919.

54,359.

Patented Jan. 20, 1920.

Inventor:

*John G. Chapman,
by his attorney
Charles R. Searle.*

UNITED STATES PATENT OFFICE.

JOHN G. CHAPMAN, OF PORT WASHINGTON, NEW YORK, ASSIGNOR TO SANFORD
NARROW FABRIC CO., OF NEW YORK, N. Y., A CORPORATION OF NEW YORK.

DESIGN FOR AN EDGING.

54,359.

Specification for Design.

Patented Jan. 20, 1920.

Application filed August 2, 1919. Serial No. 315,026. Term of patent 3½ years.

To all whom it may concern:

Be it known that I, JOHN G. CHAPMAN, a citizen of the United States, residing at Port Washington, in the county of Nassau and State of New York, have invented a new, original, and ornamental Design for an Edging, of which the following is a specification. reference being had to the accompanying drawing, which shows a strip of edging embodying my new design in elevation.

I claim:—

The ornamental design for an edging, as shown.

JOHN G. CHAPMAN.
